UNITED STATES PATENT OFFICE

2,583,445

BRASSIÈRE

Olive Ada Sabin, London, England

Application March 14, 1949, Serial No. 81,269
In Great Britain March 19, 1948

6 Claims. (Cl. 2—42)

1

This invention relates to brassières and may be applied to those with or without a diaphragm base or band, and made with cups or breast forms in one piece or in a plurality of pieces. The invention also may be applied to brassières wherein the cups are connected by material lying over the sternum and those where separate cups are provided upon a diaphragm base or band.

In wear and under the tension of the shoulder straps there is a tendency for the material of the brassière between the breasts to stand away from the figure or span the hollow over the sternum. Furthermore, although many expedients have been employed to afford the so-called uplift, including skeleton bands under the material of the cups or covering, there is still room for improvement.

The aim of the present invention is to provide improvements whereby the desired uplift may be imparted to the under bust zones of the cups while at the same time the material of the brassière or any part passing over the sternum follows the contour of the figure and lies snugly within the sternum hollow.

The invention consists in a brassière formed with a slot, gap or incision (hereinafter called gap) separating or partially separating the cups above the base line, and tension means obliquely spanning said gap and transmitting a component of the pull of each shoulder strap to the under bust zone of the opposite cup.

The above arrangement may include the modification of transmitting the pull of each shoulder strap additionally to the under bust zone of the cup to which the shoulder strap is attached.

In the accompanying diagrammatic drawings:

Figure 1 is a front elevation of a brassière according to the invention,

Figure 2 is a front elevation showing the invention applied to a brassière wherein the breast cups are joined by overlapping triangular portions,

Figures 3 and 4 are front elevations of forms of the invention having additional elastic bail means associated with the gap tension means, and

Figure 5 is a front elevation of a brassière in which means are provided for inducing an upward pull at the outer zones of the breast cups.

In carrying the invention into effect according to one mode as described by way of example, see Figure 1, the improved brassière is formed with breast cups 1, 2 of any known type and may have the under bust zone reinforced by an additional layer of fabric or stitching, extending from side

to side and adjoining the base line or band 3. At the junction between the cups 1, 2 a gap 4 is provided which extends downwardly from the upper point 5 of the junction about halfway to the band 3. The gap 4 is of open square or diamond form, with one diagonal extending horizontally and the other vertically. The opposite sides 4a, 4b and 4c, 4d of this gap are connected together by one or more elastic tapes or bands 6 and 7, respectively, so that a pull exerted on the upper side of said gap or on the adjacent upper bust portion or zone 1a or 2a is transmitted to the opposite side of the gap 4 and to the under bust portion or zone 2b or 1b of the other cup. The shoulder straps 8 are attached to the highest or mid point of the upper bust portions or zones 1a and 2a by stitching in the usual manner or by means of pulley-like rings and tapes, or in any other suitable way.

20 The gap between the bust cups may extend downwardly to the band 3 or it may extend upwardly from the band and terminate at a point spaced from the upper point 5 so that the cups are connected adjacent said point 5.

25 The invention may be similarly applied to those brassières, see Figure 2, comprising a pair of triangular shaped or folded pieces of material 9 and 10 which overlap at 11 between the breasts or over the sternum. In this form of brassière the portion towards the meeting of the upper part of the overlapping pieces has an incision which forms a gap 12 having straight sides 13, 14 and a downwardly directed point formed by sides 15, 16. This gap 12 is traversed by elastic members 17, 18 connected respectively to sides 14, 15 and 13, 16. These members 17, 18 transmit a component of the pull of each shoulder strap 19 to the opposite under bust portion or zone of the brassière cups 9 and 10 after the manner described above.

30 In the above forms the elastic members 6 and 7, Figure 1, and 17 and 18, Figure 2, may be replaced by inelastic tapes or bands, and elasticity, where required, may be introduced at the shoulder strap or in a connection thereto, for example in place of directly connecting the elastic members or inelastic members traversing the gap 4 or 12 to the upper bust portion or zone, these members may be connected by a tape or band to the shoulder strap connection, either unattached or caught to the upper bust portion.

35 In carrying the invention into effect according to another mode, see Figure 3, as applied to a brassière having a diaphragm band 20 and preferably having reinforced under bust zones

21, 22 the gap 23 in this case may extend upwardly from the diaphragm band 20, terminating at a point 24 where the upper bust portions or zones 25, 26 are connected together so that the connecting material forms the top closure of the gap. To each of the reinforced under bust zones 21, 22 bordering on the gap 23 a tab 27 of inelastic material is connected in such a way that it is directed towards the point of connection 28 of the shoulder strap 29 of the opposite cup and the end of each of these tabs 27 is stitched to a piece of elastic 30 which extends up to the shoulder strap connection and, down to the other side of the opposite cup, preferably at or about the junction between the upper edge of the reinforcement 21 or 22 and the adjacent body section 31 or 32. Thus the elastic member 30 forms a kind of bail or stirrup the mid point of which is connected to the shoulder strap 29 while the ends are, on the one hand, connected to an under bust tab 27 of the opposite breast cup and on the other hand to the outward side of the cup of the shoulder strap in question.

The shoulder strap connection may comprise a ribbon loop 33 attached to the mid point of the bail 30 at one end and at the other to the highest point 28 of the breast cup, the intervening part of the ribbon passing through a pair of shoulder strap locking attachment rings 34 of known kind. It will be observed that in this instance the components of pull of each shoulder strap 29 are transmitted obliquely to the upper bust zone of the opposite cup and to the under bust zone of the associated cup.

According to a modification of the last-described form of the invention, see Figure 4, the under bust portions 35 adjoining the gap 36 may be connected together by a short piece of elastic 37 threaded on a ring 38 which is also traversed by a band or bail 39 of elastic extending to the shoulder strap attachment and down to the outer sides of the under bust sections. This elastic 39 may, if desired, be a continuous piece, and the connection to the cups may be by means of a stirrup 40 passing pulleywise through the locking attachment rings.

The modes of carrying out the invention described above have been confined to brassières in which the cups are connected above the base line or band; the invention may, however, be carried into effect as applied to those brassières which comprise separate cups mounted on a diaphragm band. In this case the pull of the shoulder straps is transmitted across the space separating the cups by an elastic or inelastic tape or band from the point of attachment of the shoulder strap of one cup to the under bust zone of the other cup. These tapes or bands pass obliquely across the brassière and will cross one another in the space between the cups. The crossing bands may be extended stirrupwise to support the outer sides of the under bust zone of the cups, or separate tapes or bands may be connected to the outer sides of said zones and to the point of attachment of the shoulder straps. In each case described above where elastic material is specified, it will be appreciated that inelastic material may be used in substitution and any "give" or extension necessary may be provided elsewhere.

In carrying the invention into effect according to a further form see Figure 5, the breast cups 41, 42 are secured upon a diaphragm band 43 and at the region of their inner ends are cut away to form a diamond shaped gap 44 which

is spanned by pairs of elastic or inelastic straps 45, 46 similar to the form shown in Figure 1. The opening or gap 44 extends downwardly about halfway to the band 43 and from the lowest point of the diamond the edges 47, 48 of the cups overlap one another but are unconnected.

At the meeting zones of the back panels 49 and the cups 41, 42, slots or gaps 50 are provided which extend downwardly about half way to the band 43.

Each slot or gap 50 is spanned by a pair of elastic or inelastic straps 51 the ends of which are connected to the opposed edges 52, 53 of the cup and back panel.

The straps 51 may lie side by side and substantially parallel with the band 43 or may incline upwardly towards the breast cups.

A single strap or more than two may bridge the gap 50, or the gap 50 may be completely filled by an elastic insert.

With this form of the invention there is provided a more direct pull from the shoulder straps 54 to the outer side of the lower bust portion of the cups to improve the uplift characteristic.

It is to be noted that in cutting out or designing a garment according to Figure 5, the warp and weft of the fabric are arranged so that the pull from the shoulder straps 54 to the lower part of the cup in the region of the back panel takes place along the warp (or weft) indicated by the lines 55 as the case may be, and not necessarily along the edge 56 which may or may not conform to the line 55 depending upon the depth of the back panels 49.

In some circumstances the slot 50 may extend downwardly into the under bust zone.

Where the bust cups are each made in one piece with a centre dart, a piece of suitable size may be cut away from each cup adjacent the upper end of the back panel to form the slot 50.

Instead of a narrow attached shoulder strap, the strap may form an integral narrowing part of the bust cup.

Where a diaphragm band is employed the construction can be embodied as the brassière section of a combined corset and brassière called a "corsette."

I claim:

1. A brassière or like garment comprising a pair of bust supporting members operatively connected together at their inner ends; each member having shoulder strap means, each said member being cut out at the upper part of its inner end, said cut outs combining to form a gap having edges on one member opposed to edges on the other member, tension means spanning said gap and comprising superposed crossed elastic strips, the ends of each strip being secured to opposed edges of said gap and transmitting a component of the pull of each shoulder strap to the under bust zone of the other member.

2. A brassière or like garment comprising a pair of bust supporting members operatively connected together at their inner ends, each member having shoulder strap means, each said member being cut out at the upper part of its inner end, said cut outs combining to form a gap having edges on one member opposed to edges on the other member, tension means spanning said gap and comprising superposed crossed elastic strips,

65 the ends of each strip being secured to opposed edges of said gap and transmitting a component of the pull of each shoulder strap to the under-bust zone of the other member.

70 3. A brassière or like garment as claimed in

claim 2, wherein the gap is of diamond shape with a vertical diagonal and a diaphragm band connecting the two said members.

4. A brassière or like garment as claimed in claim 1 wherein the gap has upper substantially parallel edges and lower downwardly converging edges, the elastic strips being secured to a parallel edge and an opposed converging edge, said members being connected together by overlapping triangular portions.

5. A brassière or like garment as claimed in claim 2, wherein the two members have outer edges secured to back panels, the upper parts of said upper edges being cut out to form slots between the member and the associated back panel, said slots being spanned by elastic tension strips the ends of which are secured to the member and back panel, said members being connected together by a diaphragm band.

6. A brassière or like garment as claimed in 20

claim 5, wherein each slot is spanned by a pair of elastic strips which lie substantially parallel to the diaphragm band.

OLIVE ADA SABIN.
